CLAIM

The ornamental design for a frame for supporting and displaying food trays, as shown and described.

DESCRIPTION

FIG. 1 is a perspective view of a frame for supporting and displaying food tray showing my new design;
FIG. 2 is a top plan view thereof;
FIG. 3 is an elevational view of one end thereof;
FIG. 4 is a side elevational view, with the other side appearing as a mirror image thereof;
FIG. 5 is an elevational view of the other end thereof;
and,
FIG. 6 is a bottom plan view thereof.
